UNITED STATES PATENT OFFICE.

GEORGE KINGSLEY, OF LOWELL, MASSACHUSETTS.

STEAM-BOILER.

SPECIFICATION forming part of Letters Patent No. 390,235, dated October 2, 1888.

Application filed January 19, 1888. Serial No. 261,338. (No model.)

To all whom it may concern:

Be it known that I, GEORGE KINGSLEY, of Lowell, in the county of Middlesex and State of Massachusetts, have invented a new and 5 useful Improvement in Steam-Boilers, of which the following is a specification.

My invention is in the nature of certain improvements upon the steam-boiler for which Letters Patent were granted me July 31, 1883, 10 No. 282,330, and May 10, 1887, No. 362,844; and it consists in the peculiar construction and arrangements of parts which I will now proceed to describe.

Figure 1 is a vertical longitudinal section; 15 Fig. 2, a vertical transverse section; and Fig. 3 is a side view of one of the side plates of the inner shell.

In the drawings, A represents the outer shell, and B the inner shell having an arched 20 crown-sheet, with braces extending from the crown-sheet upwardly to the outer shell. The water occupies a position between the outer shell, A, and the inner shell, B, and covers the crown sheet a few inches. The boiler is 25 set with a space, I, on each side between the outer shell and the brick-work or casing, and with a space, J, beneath the boiler. The spaces I on the sides communicate at the rear end of the boiler with the fire-chamber, and, at the 30 front ends these spaces I communicate with the space J under the boiler, the spaces I and J being separated by horizontal partitions H on each side, which extend to within about four feet of the front end of the boiler. The space 35 J under the boiler at its rear end communicates with a chimney or smoke-stack, L. In the space J beneath the boiler is placed a feed-water coil and purifier, G.

Instead of using drop-tubes descending from 40 the crown-sheet for increasing the steaming capacity, as shown in my previous patents, I construct the side plates of the inner shell, as shown in Fig. 3, with screw-holes *a*, to receive side tubes, and with alternating rivet-holes *b* 45 for stay-bolts. Into the screw-holes are turned the tubes C, which are closed at their inner

ends and open at their outer ends, so as to communicate with the water-space. These tubes project laterally into the fire-space in an inclined position, being slightly higher at their 50 inner ends. Now, as the products of combustion pass through these tubes they enter the side spaces, I I, at the rear on each side, and then pass to the front, heating the outside of the shell of the boiler. Then, descending around 55 the front ends of the partitions H, they enter the space J below the boiler, where they heat the lower surface of the boiler and also the feed-water coil G, and thence pass outwardly to the rear into the smoke-stack. N is a dry-steam 60 chamber connecting with the top of the boiler by pipes P.

The advantages obtained by the inclined side tubes are as follows: First, I get with the same outer dimensions of boiler about twice 65 the amount of heating-surface that I get by drop-tubes from the crown sheet; secondly, the side tubes when inclined, as shown, allow the tubes to empty themselves when the boiler is blown off, thus cleaning themselves; thirdly, 70 there is no chance for dirt or sediment to accumulate in the tubes when the boiler is not in use or lying still, and, fourthly, the crown-sheet can be arched and thus made much stronger.

Having thus described my invention, what I 75 claim as new is—

The combination, with a double-shell horizontal boiler having an inner and outer fire-space and a water-space between, of a series of 80 inclined laterally projecting tubes, C, screwed into the inner shell, so as to communicate with the water-space, and having their inner ends closed and elevated and projecting into the inner fire-space, and the stay-bolts *c*, alternating 85 with the tubes C and connecting the shells, substantially as shown and described.

GEORGE KINGSLEY.
